UNITED STATES PATENT OFFICE.

HOWARD F. MARSTON, OF DAYTON, OHIO.

ENVELOPE-MAKING MACHINE.

1,407,206.

Specification of Letters Patent. Patented Feb. 21, 1922.

Application filed October 1, 1919. Serial No. 327,743.

To all whom it may concern:

Be it known that I, HOWARD F. MARSTON, a citizen of the United States, residing at Dayton, in the county of Montgomery and State of Ohio, have invented certain new and useful Improvements in Envelope-Making Machines, of which the following is a full, clear, and exact description.

My invention relates to an improved method for folding the bottom flap of an envelope after the two side flaps have been folded, and then transferring the blank from the folding device to a pair of rolls whereby the folds are rolled flat. The invention is susceptible of a broader application, however, in that it comprehends (1) a combined folding and gripping device, and (2) a mechanism for transferring a piece of paper from one device to another by two stages. The present embodiment of my invention is used in conjunction with a well known device for folding the side flaps of an envelope, and the usual squeezing or flattening rolls. It comprises, briefly, a segmental oscillating carrier mounted beneath the side folder. Hinged to the carrier is a bar which is brought under the flap of an envelope blank lodged in the side folder, on what will be referred to as the upward movement of the carrier, and the first function of the bar is to bend the flap upward and around the end of the folder blade forming part of the side folding device, and next to flatten out the bend by pressure between itself and the carrier. This movement of the bar is spring actuated and the folded edge of the envelope is finally gripped between the bar and carrier, so that as the carrier moves downward the envelope is drawn from the side folder and carried toward the squeezing rolls. Toward the end of the downward movement of the carrier the bar is swung back and the envelope released. Previous to this, however, a pair of hooks have been dropped over the upper edge of the envelope, and when the envelope has been released and the bar retired from its path these hooks draw the envelope down and start its lower edge, the one which was folded by the bar, in between the rolls. As the side folder merely bends the side flaps over the folder blade without flattening the bends very much, I provide a pair of rollers which bear upon these bends

as the blank moves out of the folder and roll down the folds sufficiently to fix them, so that they will not change as the blank passes between the squeezing rolls. These rollers also serve to lay the blank smoothly around the carrier, the curvature thus imparted to the blank, which is maintained by suitable guides, also serving to prevent displacement of the flaps while the blank passes from the carrier to the squeezing rolls.

The objects of my invention are seen in its functions, but one prime object is to insure greater reliability in the folding and transferring mechanism than has characterized the devices heretofore used; another is to obtain more accurate folding of the bottom flap; still another object is to enable the velocity of machines of this class to be increased. Notwithstanding the major part of the mechanism is capable of very rapid operation a machine is often incapable, as a whole, of operating at such speed, or anywhere near it, because of certain limitations of some of its parts. Therefore, elimination of such limitations is a great desideratum, and certain features in my improvement are directed to this end.

In the accompanying drawings,

Fig. 1 is a side elevation of the device, showing portions of the old mechanism and the relationship of the new to the old.

Fig. 2 is a fragmental view of the supporting structure for certain of the cams.

Fig. 3 is an end elevation of the cams.

Fig. 4 is a perspective view of my improvement, showing an envelope being drawn from the side flap folding device.

Fig. 5 is a perspective view of the carrier and bottom folding bar detached from the other mechanism.

Fig. 6 is a fragmental view showing a portion of the mechanism for controlling the folder bar.

Fig. 7 is a view to illustrate the generous curvature which is at first imparted to the paper by the folder bar.

Fig. 8 illustrates the effect of flattening the bend, showing the recession of the fold from the edge of the folder blade as the fold is flattened out.

Fig. 9 is a view of one part of the mechanism for releasing the envelope from the carrier.

Fig. 10 is a fragmental detail showing the manner of mounting the hook by which blanks are fed into the squeezing rolls.

Fig. 11 is a separate view of one of the parts shown in Fig. 10.

Fig. 12 is one of the guides for preventing lateral displacement of the blanks.

Fig. 13 shows one of the creasing rolls and the arm on which it is carried.

10 Similar numerals refer to like parts in all of the views.

Referring now to Figs. 1 and 4, the side flap folder comprises the bottom plate 25, the folder blades 26 and the folders 27 at each side, only one of which is shown (Fig. 1). Envelope blanks are fed in between the bottom plate and folder blades by means not shown. Below and about in vertical alignment with the forward edges 15 of the folder blades is a rock shaft 28 on which is fixed the segmental carrier 29. The shaft is oscillated by means not shown, Fig. 1 showing the carrier at the upper extremity 20 of its travel, while in Fig. 4 it is nearly at the lower extremity of its travel and still going down. Hinged to the lower longitudinal edge of the carrier is a bar 30 which acts both as a folder and a gripper. In Fig. 4 it is seen gripping the lower edge 25 of an envelope, the envelope being wrapped about the carrier with its top flap still between the bottom plate and folder blades. The bar is thrown into the position it occupies in Fig. 4 as the carrier nears the upper 30 end of its travel, and is thrown into the position it occupies in Fig. 5 as the carrier nears the lower part of its travel. It is retained in either of these positions by a spring 31 secured to the inside of the carrier, which 35 bears on a roller 32 mounted on a short arm extending laterally from the axis of the bar (see Figs. 1 and 6). When the bar is 40 rocked by other means to a point past the dead center, or neutral point, the spring 31 throws it the remainder of the way, imparting to it a very quick movement. The mechanism for rocking the bar will now be 45 described.

Mounted on the shaft 28 is a plate 33 having at its upper end a hole through which a rod 34 passes, (Fig. 1) the end of the rod being screwed into a collar 35 mounted on a shaft 36. The rod has a slotted head which bears against the plate 33 and by 50 turning the screw in or out the position of the plate on the shaft 28 may be adjusted, only a small range of adjustment being required. At its lower end the plate has a recess milled in it, in which is pivotally 55 mounted a lever 37; this lever is retained in its lower position by a spring 38, the movement of the lever in response to the spring being limited by the inner end of the lever bearing against a shoulder on the 60 plate formed by milling the recess. (See 65

Figs. 1 and 4). A shaft 39 is mounted in suitable journals below the free end of the lever, which shaft carries a cam 40 which at each revolution of the shaft engages a roller 41 on lever 37 and lifts the lever. An 70 arm 42 carried by the bar 30, carries a roller 43, and as the carrier nears the lower end of its travel this roller collides with the end of the lever 37. The lever is curved at the end and the roller traversing this curved 75 end rocks the bar almost to the neutral point; just at this moment the cam 40 engages the roller 41 and lifts the lever, thus throwing the bar well past the neutral point, the bar then being thrown clear down 80 by the spring 31. While I have found it feasible to depend entirely upon the curved end of the lever acting on the bar by virtue of the movement of the carrier, I prefer to supplement this with the cam, which acts 85 very quickly and can be set to act at a certain time with reference to the other parts of the mechanism.

For operating the bar 30 at the upper end 90 of the carrier travel, I provide a lever 45 which is loosely mounted on shaft 28 and normally held against an adjustable stop 46 by a spring 47. At its lower end this lever carries a roller which at each revolution of shaft 39 is engaged by a cam 48, thus 95 rocking the upper end of the lever forward; i. e., toward the approaching carrier. Connected to the upper end of lever 45 by an adjustable attachment is an arm 49. This arm is also loosely mounted on shaft 28, so as 100 to enable the shaft to rotate within it, and it carries a cam 50, the position of the cam on the arm being adjustable. The cam has two working faces, which for the purpose of description may be the portions above 105 and below, respectively, of the line $a-a$ drawn across the cam in Fig. 4. As the carrier approaches the upper end of its travel the bar 30 being in the position it occupies in Fig. 5, the roller 43 collides with 110 the portion of the cam below the line $a-a$ and as the carrier continues its movement the roller runs downward on the cam and the bar 30 is rocked on its axis toward the position it occupies in Figs. 1, 4 and 6. At 115 the appropriate moment the cam 48 engages the roller at the end of lever 45, which it has just done in Fig. 1, and rocking the cam 50 forward quickly rocks the bar 30 past the neutral point, the spring 31 then completing the movement of the bar. By means 120 of the adjustment between the lever 45 and the arm 49 the mechanism may be timed to throw the bar 30 over at just the proper moment.

Previous to the carrier reaching its upward position and the bar being swung to gripping position, an envelope blank will have entered the space between the bottom plate 25 and plates 26, and the side folders 130

27 will have folded the side flaps over the blades 26. At this time the bottom flap of the blank projects out over the carrier. As the bar 30 is swung to its gripping position 5 it lifts this flap and carries it around the ends of the folder blades. The paper having a certain resiliency the bend at first formed has a rather generous curvature. This is 10 illustrated in Fig. 7 where the paper, indicated by the numeral 51, is seen to form a curve of comparatively large radius, although at one point it touches the folder blade. As the bar assumes its gripping position this curved fold is gradually flattened 15 out, and as friction prevents the paper slipping on the bar, it follows that flattening the fold causes its recession from the edge of the blade 26, this being illustrated in Fig. 9 where in dotted lines is shown the paper 20 as it would appear were the fold not flattened out and in full lines the flattened fold. It will be readily seen that if the fold is made quite flat it will have receded from the edge of the blade a distance equal to approximately half of the distance around the large 25 curve shown in dotted lines. The carrier is so located with reference to the front edge of the blades 26 when at the extremity of its upward movement that the flattened fold 30 is nearly, if not quite, at the throat of the gripper; i. e., the junction of the bar 30 with the carrier 29. Because of the curvature of the carrier, the face of the bar being straight, or even curved slightly upward, the blade 26 35 is not gripped. In other words, by reason of the recession of the fold as above described, the gripper is enabled to seize the paper without gripping the blade, it being understood that the edge of the blade is quite thin. 40 In rare cases; for example, where very soft thin paper is being used, the recession of the fold may be found to be so slight as not to enable the gripper to seize the paper without also gripping the blade. In such case I may 45 secure a small piece of rubber 52 on the carrier (see Fig. 5) so located that it will be under the blade 26 when the carrier is in its upper position. This will increase the friction between the paper and the carrier 50 and assist in drawing the paper away from the blade 26. While the spring 31 actuates the carrier with sufficient force to flatten out the fold of most grades of paper, aided as it is by momentum imparted to the bar 30 by 55 the cam 50, which itself is given a very rapid movement by the cam 48, the portion of cam 50 above the line $a-a$ is arranged to run under the roller 43 and by lifting the arm 42 press the bar 30 down on the folded paper. In Fig. 1 this is about to occur; in 60 this figure it is assumed that the carrier has reached its uppermost position and during the instant that it remains there the cam 48, which it will be observed has not 65 yet completed the movement of the lever 45,

rocks the lever far enough to move the cam 50 out under the roller 43, thereby pressing the bar 30 down on the paper and flattening the fold if it has not already been flattened.

A frame comprising arms 55 and 56 is 70 mounted to rock on pivots 57 carried by the frame-work of the machine. Each of these arms carries a roller 58, the arm 56 also carrying a roller 59. This roller rides on a cam 60, whereby it is raised at certain 75 times and at other times allowed to drop so that the rollers 58 ride on the carrier 29; this movement is aided by a spring 61. As the carrier starts downward, carrying an envelope blank, the frame is dropped, the 80 rollers 58 riding on the folded sides of the blank. In order to more readily equalize the pressure, or rather to insure that both rollers 58 rest on the blank, I mount one of the rollers 58 on a yielding arm 62, carried by arm 55. The slight pressure of the 85 rollers, together with the restraint imposed upon the blank by the blade 26 on which the side-flaps still lie, wraps the blank smoothly about the carrier. The cam 60 is 90 secured to a sleeve 63 which is loosely mounted on shaft 28, the sleeve also carrying a gear 64, this gear being rotated by gearing not shown. This portion of the structure 95 will be further described presently.

Shaft 39 has rigidly secured to it a roller 65 which, together with a roller 66 rigidly secured to a shaft 67, constitutes what has heretofore been referred to as the squeezing rolls. These rolls rotate constantly in the 100 direction shown by the arrows on their ends and as the carrier nears its lowermost position, and after the bar 30 has been swung back to release the envelope, the envelope is caught by a pair of hooks 68 whereby it is 105 drawn down and fed between the squeezing rolls. The hooks are pivotally attached to blocks 69 which are rigidly secured to a rod 70 carried by a pair of arms 71, the arms being rigidly secured to a rock shaft 72, said 110 shaft also carrying an arm 73 having a roller 74 at its end which lies on a cam 75 carried by the sleeve 63. The arms 71 are drawn downward until they rest on stops 76 by a spring 77 seen in Fig. 1, and the hooks 68 115 are lightly pressed downward by springs 78 (see Fig. 10), the lower position of the hooks being determined by lugs extending laterally from the blocks 69, on which the hooks rest (see Figs. 10 and 11).

As the carrier rocks downward the arms 71 rock upward, and shortly before the top flap of the envelope passes from beneath the folder blades 26 the hooks drop behind the edge of the flap, notches 79 being formed in 120 the blades for the accommodation of the hooks. For the same purpose grooves 80 are formed in the carrier 29. When the envelope has been released from the carrier 125 the arms 71 move downward, the hooks 130

drawing the envelope down until its lower edge passes between the squeezing rolls. The cams 60 and 75 are adjustably secured to the sleeve 63, as is clearly seen in Fig. 3, 5 and by means of this adjustment, together with the adjustment (not shown) whereby the cam 40 can be set to trip the bar 30 at just the required time the functions of the several parts of the mechanism can be so 10 coordinated as to fully control the passage of the blanks through the device, regardless of the velocity at which the machine is operated.

The paper usually has sufficient resiliency 15 to insure its lower edge springing out so as to clear the hinge of the bar 30. Under some conditions, however, it may be necessary to insure the envelope not catching on the hinge as it is drawn from the carrier by 20 the hooks 68, and for this purpose I have provided plungers 85 which are projected from their normal retirement at about the time the bar 30 is thrown back to release the envelope. These plungers are pivotally attached to collars 86 loosely mounted on shaft 28 and are normally held in retirement by 25 springs 87 secured to the collars and the carrier 29. This will be understood by reference to Fig. 5, in which one of the plungers and collars is shown, the shaft 28 being 30 shown in dotted lines. It will be seen that the spring 87 is adapted to rotate the collar 86 on the shaft counter-clockwise until the plunger, at a point intermediate its ends, 35 collides with the bottom of the shaft. At this time the end of the plunger will be about flush with the outer surface of the carrier. The collars are provided with projecting studs 88 (see also Fig. 1) which, when 40 the carrier has nearly reached its lowermost position, impinge on the rock shaft 72, thereby checking the rotation of collars 86. Because of the tangential relation of the plungers to the shaft, continued movement of 45 the carrier after the collars 86 have been arrested shortens the distance from the point at which the plungers pass through the carrier and the point where they are attached to the collars, thereby projecting the plungers outward and pushing the envelope 50 clear of the hinge. It will be noted that in Fig. 5 the plunger protrudes slightly from the carrier, while it is not quite in contact with the shaft.

55 I provide a system of guides which insures the envelopes against misdirection during their transfer from the carrier to the squeezing rolls. One of these comprises a plate 90 which is supported by being secured to a bar 60 91 forming part of the frame of the machine. This plate is given a curvature substantially concentric to the shaft 28 and prevents displacement of the envelope outward as it passes from the carrier to the 65 rolls. At the left hand end of the rolls I

provide a stationary guide 92, carried by the frame of the machine, which extends toward the shaft 28 far enough to overlap the carrier when the latter is down. At the right hand end of the rolls I provide a similar 70 rigid guide, 93, but to avoid interference with the arm 42 and roller 43 I have made it shorter than the guide 92. To co-operate with and complete this guide I mount a plate 94 on the right hand end of the carrier. 75 This plate is secured to a lever 95 which is pivoted to the end of the carrier. Normally this plate is held by a spring 96 in a position where the plate does not extend beyond the perimeter of the carrier, it being thus kept 80 out of the way of the roller 58 when the carrier is up. The free end of the lever, 97, is adapted to collide with an adjustable stud 98 as the carrier approaches its lower position, which rocks the plate outward into the 85 position it occupies in Fig. 4. In this position the plate co-operates with the short guide 93 and prevents lateral displacement of the envelope to the right. On a stationary rod 100 I mount blocks 101, which carry 90 guide arms 102 shown mostly in dotted lines in Fig. 1, grooves being formed in roller 65 to accommodate the guides. By means of these several guides the envelope is accurately guided during its transfer. 95

As the various parts of this device have been described in substantially the order in which they act on an envelope, the function and operation of each part being fully described, it is deemed unnecessary to review 100 the operation. As previously stated one of the objects of my improvement is to enable a machine of this class to be speeded up; paper being a very erratic material to operate upon and affected by a number of extraneous conditions and influences, such as moist atmosphere or static electricity, for example, it is necessary to provide some safeguards which are not essential in most cases or under ordinary circumstances. On 110 the other hand, since one or another unfavorable condition is liable to occur unexpectedly, and as conditions often change quickly, it is desirable to have the various provisions for taking care of abnormal conditions operative all the time. This being so, it is important for these provisions to be practicable for constant operation, and without incumbering or unduly complicating the machine. My improvement successfully 120 meets these several requirements, and while I have described what at this time seems the preferred embodiment of the various devices, it is not to be understood that I limit myself to the particular details of construction shown. 125

What I claim is as follows:

1. In an envelope making machine, in combination with the folder blade and squeezing rolls, an oscillating carrier 130

- equipped with a folder bar, means for actuating said bar to fold the bottom flat of an envelope around the folder blade and then grip the envelope and hold it on the carrier 5 while the carrier moves from the folder blade to the squeezing rolls, and independent of the folder bar means for starting the envelope between said rolls.
2. In an envelope making machine, in combination with the folder blade and squeezing rolls, a carrier equipped with a folder bar, means for actuating said bar to fold the bottom flap of an envelope and then grip the folded edge, holding the envelope on the carrier while the carrier moves from the folder blade to the squeezer rolls, means for releasing the envelope from and retiring said folder bar, and hooks which engage the envelope and draw it down until it enters between the rolls.
3. In an envelope making machine, in combination with the folder blade and squeezing rolls, a segmental carrier equipped with a folder bar, adapted to move to a position with the folder bar under the bottom flap of an envelope blank, means for actuating the bar to fold the flap over the folder blade and then grip the blank and hold it while the carrier moves to the squeezing rolls, creasing devices for bending the envelope around the carrier, means for releasing the envelope from and retiring the folder bar, and hooks whereby the envelope is drawn from the carrier and started between the squeezing rolls.
4. In an envelope making machine, a side-flap folding mechanism, squeezing rolls, a combined bottom folder and carrier, whereby the bottom flap of an envelope is folded 40 and the envelope carried from the side-flap folding mechanism, means for releasing the envelope from the carrier, and means for starting it between the squeezing rolls after it is released.
5. In an envelope making machine having a device in which an envelope blank finds temporary lodgment and a second device to which the blank must be transferred, a carrier equipped with a gripping device whereby the blank is drawn from the first device, means for releasing the blank from said carrier, and means independent of the carrier for delivering the blank to said second device.
6. In an envelope making machine having a device in which an envelope blank finds temporary lodgement and a second device to which the blank must be transferred, a carrier equipped with a gripping device whereby the blank is drawn from the first device, means for releasing the blank from said carrier, and members independent of the gripping device whereby the envelope is pushed into the second device.
7. In an envelope making machine having a device in which an envelope blank finds temporarily lodgment and a second device to which the blank must be transferred, a segmental carrier adapted to oscillate between said devices, a gripping bar hinged thereto, means for throwing the bar into gripping position when it arrives at the first device, thereby seizing the envelope, and means for throwing the bar to retired position after the carrier has rocked away and removed the envelope from said device, thus releasing the envelope from the carrier and permitting it to pass to the second device.
8. In an envelope making machine having a device in which an envelope blank finds temporary lodgment and a second device to which the blank must be transferred, a segmental carrier adapted to oscillate between said devices, a gripping bar hinged thereto, means for throwing the bar into gripping position when it arrives at the first device, thereby seizing the envelope, means for throwing the bar to non-gripping position after the carrier has rocked away and removed the envelope from said device, thus releasing the envelope from the carrier, and means for delivering the envelope to the second device.
9. In an envelope making machine having a device in which an envelope blank finds temporary lodgment and a second device to which the blank must be transferred, a segmental carrier adapted to oscillate between said devices, a gripping bar hinged thereto, spring actuated means for throwing the bar to gripping or retired position after it is starting by other means past a neutral position, means for starting the bar to gripping position after the carrier arrives at the first device and means for starting it toward the retired position after the blank has been removed from the device, a rocking frame carrying hooks adapted to drop over the rear edge of the blank and draw it into the second device, and means for rocking said frame in synchronism with the movements of the carrier.
10. In an envelope making machine having a device in which an envelope blank finds temporary lodgment and a second device to which the blank must be transferred, a segmental carrier adapted to oscillate between said devices, a gripping device mounted on the carrier whereby the blank is seized and drawn from the first device as the carrier moves away therefrom, means for releasing the blank and retiring the gripping device, and plungers whereby the blank is pushed away from the carrier after its release.
11. In an envelope making machine, a shaft, a segment of a cylinder mounted to rock thereon, a combined folding and gripping bar hinged thereto, a lever mounted to rock on the shaft for the purpose of actuat-

ing the folding bar, a cam to rock the lever, and means for adjusting the lever so it will act at a given time with reference to the position of the segment.

- 5 12. In an envelope making machine, a combined folder and gripping device, comprising a bar hinged to a movable carrier, and means for bringing said carrier into position below the unfolded flap of an envelope blank; an arm extending from said bar, a two faced cam, with one face of which said arm collides as the carrier comes into position under the blank and whereby the bar is swung on its hinge so as to fold the 10 flap around the folder blade under which it is held, a spring whereby movement of the bar is continued after it is swung a certain distance by the cam, thereby bringing the arm into the sphere of action of the other 15 face of the cam, and means for moving the cam to act on the arm and supplement the action of the spring.

13. In an envelope making machine, a shaft, a segment of a cylinder mounted to 20 rock thereon, a combined folding and gripping bar hinged thereto, an arm engaged by a part of the bar as the segment approaches one extremity of its stroke, whereby the bar is swung on its hinge and made to release a 25 blank in its grip, and means for adjusting the position of said arm, so as to release the blank at a given time during the movement of the segment.

14. In an envelope making machine, a 30 combined folder and gripping device, comprising a bar hinged to a movable carrier, means for operating the bar to fold the flap of an envelope blank and then to grip the creased edge thereof; and means for swinging the bar back to release the envelope, comprising an arm with which a part of the 35 bar collides, said arm having a form of such character as will produce movement of the bar on its hinge by virtue of the carrier 40 movement, and means for imparting movement to the arm at a predetermined time whereby the movement of the bar on its hinge is accelerated.

15. In an envelope making machine, an 45 oscillating carrier, squeezing rolls, a rocking frame carrying hooks adapted to drop behind an envelope blank on the carrier and draw it into the rolls, and cam mechanism for actuating the frame.

50 16. In an envelope making machine, squeezing rolls, a folding device, hooks adapted to seize an envelope blank as it emerges from the folding device and feed it in between said rolls, and guides between 55 which the blank is confined to prevent lateral displacement thereof.

17. In an envelope making machine, squeezing rolls, a folding device, hooks adapted to seize an envelope blank as it 60 emerges from the folding device and feed it

in between said rolls, guides between which the blank is confined to prevent lateral displacement thereof, and back and front guides to insure proper entry of the blank 70 between the rolls.

18. In an envelope making machine, an oscillating carrier, squeezing rolls, a rocking frame carrying hooks adapted to drop behind an envelope blank on the carrier and draw it into the rolls, a cam for lifting the 75 frame to enable the hooks to grasp the blank, a spring to return the frame, and stops to limit the return movement of the frame.

19. In an envelope making machine, squeezing rolls, a carrier whereby envelope 80 blanks are carried from a folding device to a position from which they may be fed in between said rolls, a guide on said carrier to prevent lateral displacement of the blank, and means for retiring said guide during a 85 portion of the carrier's cycle of movement in which it is not needed and for restoring it to its effective state.

20. In an envelope making machine, squeezing rolls, a carrier whereby envelope 90 blanks are carried from a folding device to a position from which they may be fed in between said rolls, a stationary guide member supported independently of the carrier and a guide member carried by the carrier, 95 the two forming a guide to prevent lateral displacement of the blank, and means for retiring the latter member during a portion of the carrier's cycle of movement in which it is not in use and for restoring it when 100 needed to co-operate with said stationary member.

21. In an envelope making machine, in combination with a segmental carrier and means thereon whereby an envelope blank is 105 drawn from a flat folding device where the end flaps have been folded, a pair of stationary creasing rolls whereby the folded ends of the blank are rolled down so as to fix the folds and wrap the blank smoothly 110 around the carrier.

22. In an envelope making machine, in combination with a segmental carrier, whereby an envelope blank is drawn from a flat folding device where the end flaps have 115 been folded, a frame carrying two creasing rolls whereby the folded ends of the blank are rolled down so as to fix the folds and wrap the blank smoothly around the carrier; one of said rolls being mounted directly on 120 the frame, the other being yieldingly mounted with reference to the frame.

23. In an envelope making machine, a combined folding and gripping device, comprising a folder blade, a carrier close thereunder but sufficiently removed to admit an envelope blank between them, a folder bar hinged to the carrier and adapted in conjunction therewith to form a gripper, their relationship being such that the gripping func- 125 130

tion is effected close to the axis of the hinge, and means for rocking the bar about its axis, carrying a protruding flap of the blank with it and bending it around the blade, the edge 5 of the blade being far enough removed from the throat of the gripper to permit of the paper assuming a relatively large curvature, thereby providing enough paper to throw the crease which is formed when the fold is 10 flattened by the gripper a substantial distance from the edge of the plate, thus affording a hold on the blank for the gripper beyond the blade.

24. A combined folder and gripper, comprising two elements hinged to each other, adapted to close together and grip what is in their throat; a folder blade therebetween, the edge of the blade being removed from the throat far enough to be out of the range 20 of its grip; and means for introducing the paper to be folded in such manner that it is bent around the edge of the blade as the elements close together, allowing the paper to assume at first such a curvature as its 25 resiliency tends to produce, the bend then being gradually flattened to a crease and concurrently receding from the edge of the blade, thereby enabling the gripper to grip the folded paper without gripping the blade.

25. In an envelope machine, in combination with a folder blade, a shaft therebelow, a segmental carrier mounted to rock thereon, a folder bar hinged to the lower longitudinal edge thereof, said bar having protruding 30 arms carrying rollers, leaf springs on the carrier bearing against the rollers and adapted to throw the bar to either its open or closed position after it is moved by other means beyond a neutral position, an operating 35 arm protruding from the bar and carrying a contact roller, a lever located in the path of said roller whereby the bar is swung toward its closed position as the carrier rocks to a position beneath the folder blade, the 40 springs completing the movement of the bar and pressing it against the carrier, thereby folding the bottom flap of the envelope around the blade and gripping the envelope so that as the carrier rocks from beneath the 45 blade it carries the envelope with it; and an arm with which the contact roller engages at the proper time for returning the bar over said neutral position, the springs then throwing it to its open position, thus removing 50 it from the path of the envelope.

26. In an envelope machine, in combination with a folder blade, a shaft therebelow, a segmental carrier mounted to rock thereon, a folder bar hinged to the lower longitudinal 55 edge thereof, said bar having protruding arms carrying rollers, leaf springs on the carrier bearing against the rollers and adapt-

ed to throw the bar to either its open or closed position if it is moved by other means beyond a neutral position; an operating arm 65 protruding from the bar and carrying a contact roller, a lever located in the path of said roller whereby the bar is swung toward its closed position as the carrier rocks to a position beneath the folder blade, the 70 bar being swung nearly to said intermediate position by the time the carrier comes to rest; means for advancing the lever after the carrier comes to rest, throwing the bar past the neutral position, the bar in closing 75 folding the bottom flap of the envelope over the blade and then gripping the folded edge so that as the carrier rocks from beneath the blade it carries the envelope with it; and an arm with which the contact roller 80 engages at the proper time for returning the bar over said neutral position, the springs then throwing it to its open position, thus removing it from the path of the envelope.

27. In an envelope machine, in combination with a folder blade, a shaft therebelow, a segmental carrier mounted to rock thereon, a folder bar hinged to the lower longitudinal edge thereof, said bar having protruding arms carrying rollers, leaf springs on the 85 carrier bearing against the rollers and adapted to throw the bar to either its open or closed position if it is moved by other means beyond a neutral position; an operating arm protruding from the bar and carrying a contact roller, a lever located in the path of said roller whereby the bar is swung toward its closed position as the carrier rocks to a position beneath the folder blade, the 90 springs completing the movement of the bar and pressing it against the carrier, thereby folding the bottom flap of the envelope around the blade and gripping the envelope so that as the carrier rocks from beneath the 95 blade it carries the envelope with it; a frame carrying creasing rollers whereby the folds of the side flaps are maintained as the envelope is drawn off of the folder blade and wrapped around the carrier, a cam for raising the frame so the creasing 100 rollers will be out of the way of the folder bar as it is swung to closed position; and an arm with which the contact roller engages at the proper time for returning the bar over said neutral position, the springs 105 then throwing it to its open position, thus removing it from the path of the envelope.

In testimony whereof I affix my signature in the presence of two subscribing witnesses:

HOWARD F. MARSTON.
